UNITED STATES PATENT OFFICE

2,618,483

BASEBALL AND MINIATURE GOLF APPARATUS

Phillip William Chiodo, Niagara Falls, N. Y.

Application November 16, 1948, Serial No. 60,287

2 Claims. (Cl. 273—90)

1

This invention relates to game apparatus. One object is to provide a game which combines the features of baseball and miniature golf. A further object of the invention is to provide a game of the character above set forth that can be played indoors or out of doors, that will have all the advantages of golf, on a miniature scale, and that will afford amusement and exercise for adults as well as for children. The nature of the invention, together with its many other objects and advantages will be better understood from a study of the following description, taken in connection with the accompanying drawings wherein:

Fig. 1 is a perspective view of a playing field constructed in accordance with the present invention.

Fig. 2 is a longitudinal sectional view through a ball delivery chute.

Fig. 3 is a vertical sectional elevational view showing a ball raising mechanism arranged in one of the ball paths of the playing field substantially on the line 3—3 of Fig. 1.

Fig. 4 is a sectional elevational view clearly illustrating one of the hazards forming part of the invention, taken on the line 4—4 of Fig. 1.

Fig. 5 is a sectional elevational view illustrating another of the hazards and taken on the line 5—5 of Fig. 1.

Fig. 6 is a sectional elevational view illustrating another hazard forming part of the invention and taken on the line 6—6 of Fig. 1.

Fig. 7 is a vertical transverse sectional view taken through the ball chute on the line 7—7 of Fig. 1.

Fig. 8 is a sectional elevational view illustrating another of the hazards forming part of the invention, taken on the line 8—8 of Fig. 1, and

Fig. 9 is a view in perspective of a wicket forming a part of one of the hazards.

Referring more in detail to the drawings, particular attention being directed to Fig. 1, it will be seen that the playing field somewhat in the nature of a baseball diamond includes base path 5 together with a path 6 leading from the home base into the infield and terminating in an enlarged somewhat circular portion symbolic of what is known in baseball as a pitcher's box and designated by reference character 7.

The parts of the playing field thus enumerated are preferably constructed of cement 8 arranged in a frame structure of wood or similar material 9. The paths are of suitable width and the playing field is preferably set up on a lawn or at any desired location out of doors with the

2

area surrounded by the base paths being platted with grass to simulate the infield of a baseball field.

Instead of the usual bases there is provided at the junction of the base path, for the purpose of bringing into the game certain features of golf, a hole 10 within which is arranged an open ended cylinder 11 having operable therein a reciprocable piston 12 for elevating the ball so that the same may be teed to be driven to the next hole.

Suitable mechanism is provided for raising and lowering the piston 12 and as shown in Fig. 3, such mechanism consists in the present instance, of a lever 13 pivoted intermediate its ends to a hanger 14, the hanger and lever being arranged in well 15 suitably provided in the ground beneath the surface of the ground. The lever 13 is pivotally connected with the piston 12 through the medium of a link 16 and at its free end has a loose connection 17 with a vertically movable foot pedal 18 operable in a guide 19 provided therefor.

Manifestly, to raise a ball that has dropped into the hole 10 the pedal 18 is depressed by foot causing lever 13 and link 16 to move the piston 12 upwardly flush with the surface of the base path whereupon the ball may be driven along same.

Arranged on the base path 5 between the holes 10 are suitable hazards as for example a hazard 21, as more clearly shown in Fig. 4, which consists of vertical spaced posts 22 connected by horizontal bars 23, and it will be found in actual practice that considerable skill will be required in order to drive a ball along the path 5 between two adjacent posts 22 without the ball being driven against one of the posts before such success is attained. In Fig. 5 I have shown another form of hazard which in this instance consists of two hinged gates 24 opposed posts 25 being provided for hingedly supporting the gates.

In Fig. 9 I have shown a somewhat conventional garden wicket 26 and a row of such may be placed across the base path 5 as for example between the holes indicative of the home plate and the hole indicative of first base. On the path 6 and extending for substantially the full length thereof is arranged a ball chute which leads from the pitcher's box 7 to the hole 10 located at that part of the playing field as would, in the case of baseball, be located the home plate. The ball chute is substantially U-shaped and includes an upper inclined part 27 substantially

channel shaped in cross section for the major portion of its length and supported by relatively spaced standards 28. The ball chute also includes a lower or bottom part 29 that for substantially half of its length is channel shaped in cross section and at its end terminates in operative position to the hole 10 that is aligned with the path 6.

The bight and portion of the parts 27 and 29 of the chute are substantially tubular in cross section as at 30 so as to guide a ball 20 in its course from the upper part 27 to the lower part 29.

Obviously a ball placed in the upper end of the part 27 will by gravity roll down said part 15 through the tubular part 30 and along the part 29 to discharge therefrom, the object being that a party stationed near the discharge end of the path 29 and provided with a suitable golf club as for example a putter, strike the ball while 20 the same is in motion and immediately upon its discharge from the ball chute, the object, purpose and intent being to drive the ball along the base bath 5 in a direction toward the right in Fig. 1 to the first hole 10.

When a player has been successful in "sinking" the ball into the first hole 10, he, or another player depresses the pedal 18 to actuate the piston 12 of that particular hole to raise the ball to the surface of the path 5 whereupon the player 30 drives the ball over the path 5 to the next hole 10, play being continued in this manner until a player has negotiated one round trip. Obviously the rules of the game may be as desired by the players, as for example the one may be 35 declared the winner who has negotiated all of the holes with the least number of strokes, or in the shortest period of time, or as otherwise may be found desirable.

To further add to the attractiveness of the 40 game, and to render the same more similar to golf, there may be arranged in the path 5 holes 31 forming water or sand traps as may be found desirable.

Also, another type of hazard which I have 45 found requires a great deal of skill to negotiate is such as suggested in Fig. 8 wherein I have shown three relatively spaced open ended tubes 32 and which are elongated lengthwise of the path 5, the object being to drive the ball through 50 or between the tubes.

It is thought that from the foregoing description, taken in connection with the accompanying drawings that a clear understanding 55 of the construction, as well as the purpose, ob-

ject and intent of the invention will be apparent to those skilled in the art.

Even though I have herein shown and described the preferred embodiment of the invention, it is to be understood that the same is susceptible of changes, modifications and improvements coming within the scope of the appended claims.

What is claimed is:

1. A game device of the character described comprising: a playing surface shaped in the form of a baseball diamond comprising a home plate, first, second and third base, and a pitcher's box, said playing surface further comprising a playing path having a paved surface joining said home plate and all of said bases in the order named and having a ball receiving aperture therein at home plate and at each of said bases; and ball delivery means comprising a ball guiding portion extending from said home plate to said pitcher's box and back to said home plate, said ball delivery means further comprising a portion adjacent to said home plate wherein a ball traveling along said guiding portion from said pitcher's box toward said home plate will be clearly visible to a player standing at said home plate, said ball guiding portion being directed to deliver said ball in a path of travel on said playing surface, crossing said paved playing path at a portion thereof adjacent to home plate.

2. A game device according to claim 1, further comprising at least one obstacle disposed in said playing path, whereby greater skill is required to play a ball from a position adjacent one of said ball receiving apertures along said path and into another such aperture.
